UNITED STATES PATENT OFFICE

2,480,695

STEEL FLOOR FOR REFRIGERATOR CARS

Edwin R. Battley and George E. McCoy,
Montreal, Quebec, Canada

Application January 26, 1945, Serial No. 574,788

16 Claims. (Cl. 105—422)

1 The invention relates to metal floors for refrigerator cars and more particularly to such floors for refrigerator cars of the overhead bunker type.

The invention is an improvement over the invention disclosed in Patent No. 2,136,999 of November 15, 1938, wherein refrigerant containers are located adjacent the roof and side walls of the car, a drip pan is located below the refrigerant container to provide an air cooling space therebetween, flues are associated with the side walls, which flues communicate with said air cooling space and with a space below the lading supporting rack, and wherein air in said space, cooled by the refrigerant in said container, descends through said flues into the space below the lading, and being warmed by said lading, rises through said rack and lading to the cooling space where the cycle is repeated.

The conventional refrigerator car floor is of wood with insulation thereunder and may be lined with a metal floor sheet to aid in keeping the wood and insulation dry. Without such lining moisture seeps through the floor and into the insulation causing it to become soggy and generally worthless as an insulating medium, besides such moisture adding as much as several tons to the weight of the car which must be moved with the car, at, of course, added expense.

It is consequently the principal object of the invention to provide a metal floor lining which extends to the side walls of the car and is secured to structural parts of said side wall so as to provide a watertight joint.

A further object is to so shape said joint so that it adds strength to the wall and also acts to prevent, or at least, materially retard the surging of liquid, due to service movements of the car, which may be on said floor or in a gutter formed at the juncture of said wall and floor.

Another object of the invention is to provide a metallic floor formed in a plurality of sections, the adjacent sections on one side of the car being joined to the like sections on the opposite side by an upstanding central longitudinal seam.

Another object of the invention is to provide a metallic floor formed in a plurality of sections each extending crosswise from side wall to side wall, or from gutter to gutter, the sides of adjacent sections being formed with upstanding flanges which are secured together and to a hold-down strip secured to the car sub-floor.

Another object of the invention is to provide a gutter at substantially the juncture of the floor with each side wall in each floor section, and to

2 provide a drain for said gutter in each section, said gutter sloping from opposite ends toward said drain.

A further object is to provide an inner side sill having a portion cooperating with the sides of the floor sheet and lower edge of the flue sheet so that they may be united by welding or otherwise and thereby form the aforesaid joint.

Other objects and advantages of the invention will appear in the following description thereof.

Referring now to the accompanying drawings forming part of this application and wherein like reference characters indicate like parts.

Figure 1 is a partial cross section of a refrigerator car incorporating the invention.

Figure 2 is a perspective view of the construction shown in Figure 1.

Figure 3 is a partial transverse section of a modified form of floor sheet, with the gutter omitted.

Figure 4 is a diagrammatic plan view of a car provided with the improved floor sheet.

Figure 5 is a diagrammatic section of the floor sheet on line 5—5 of Figure 4.

Figure 6 is a diagrammatic section of the floor sheet on line 6—6 of Figure 4.

Figure 7 is a view similar to Figure 1 of a modified form of the invention wherein a separate gutter is shown and the floor sheets extend transversely of the car between the gutters.

Figure 8 is a section on line 8—8 of Figure 7.

Figure 9 is a plan view of a modified form of hold-down means for said floor.

Figure 10 is a partial cross sectional view of a refrigerator car showing a modified form of the invention.

In the drawings the usual parts of a car are shown, such as the side sill 1; floor rack 2 supported on transverse stringers 3 to provide a space 4 between said racks and the floor proper.

The side wall comprises outside sheathing 5 attached at its lower edge to a vertical arm of the side sill 1, a plurality of layers of insulation 6, a plurality of longitudinally spaced ducts or flues 7, spaced posts 8, nailing strips 9 and inner lining 10. The side wall is thus adapted for use with the overhead bunkers, the side wall flues 7 conducting chilled air from a refrigerant compartment adjacent the car roof to the space 4 between the floor and floor rack 2.

The floor of the car comprises a metallic protecting sheet 12, a wooden sub-floor 13, plies of insulation material 14 and lower metallic sheet 15.

As will be observed from Figure 4 there are eight floor protecting sheets 12, although there

may be more in the case of a larger car, or for practical reasons, each of said sheets having an upstanding flange 16 at one side thereof, which, when the sheet is in place within the car, is adjacent the longitudinal center of the car. The 5 opposite side of the sheet is formed with a depression, indicated at 17, the outer wall 18 of which depression is formed on a substantial radius (to provide resiliency for adjustment of parts) and is provided with a downwardly and inwardly extending reflare 19 for purposes which will hereinafter appear. The depression 17, of course, occurs adjacent the bottom of the side walls and forms a gutter to carry away meltage or overflow from the refrigerant, or water used in flushing the floor for cleansing purposes. It will be noted in Figures 1 and 3 that the floor sheets are preferably arranged so that they slope 10 downwardly from the longitudinal center of the car to the gutter on either side thereof to provide adequate drainage thereto. At approximately midway the length of the gutter of each sheet there is provided a drain 21, and in Figure 5 it will be observed that the gutters 17 slope from opposite ends toward said drains. 15 At the ends of each floor sheet are provided upstanding flanges 22 similar to flanges 16.

In Figure 6 it will be noted that the floor proper slopes in a single plane from adjacent the longitudinal center 23 of the car to the edge of the 20 gutter 17.

The vertical nailing strips 9 and posts 8 rest upon the longitudinally disposed portion 24 of an inner sill which is substantially a slightly deformed Z-bar having a vertical flange 25 extending upwardly from the inner edge of the portion 24 and terminating in an outwardly and downwardly turned reflare 26 overlying the reflare 19 of the floor sheet, to which it is welded, as 25 at 27.

The sheet forming the flues 7 is shown as having a lower margin 30 integrally formed therewith and extending downwardly and inwardly in approximately the plane of reflanges 19 and 26 upon which the free edge of said margin 30 rests and is welded thereto, as at 31. It will be noted that the reflanges 19 and 26 and edge of margin 30 terminate successively short of each other to provide grooves for welding, but obviously they could terminate flush with each other and possibly be secured together by a single line of welding and fall within the scope of the invention. There is thus provided a watertight seam of the bottom of the flues with the floor sheet so that water cannot pass therethrough into the car insulation.

In Figure 7 there is shown a modified form of the invention wherein the gutter 40 is formed of a separate sheet of material so that it may be of heavier gauge or of a corrosion resisting material. In this construction the outer wall 41 is welded, as at 42, directly to the posts 8 preferably independently of the inner side sill 43. The lower margins 44 of the flue sheet 45 terminates in a depending flange 46 overlapping the downwardly inclined flange 47 of the gutter wall 41 and cooperates therewith in further retarding splashing of water in the gutter. Flange 46 is attached to the gutter flange 47 in any acceptable manner.

The inner gutter wall 50 is provided with a stiffening flange 51 to support the floor sheet 52. The floor sheet overlaps and rests upon the flange 51 of the gutter wall 50 and is preferably welded thereto, as shown at 54.

In Figure 8 there is shown a preferred means of securing the floor sheets to the car. An angle strip 57 is secured to the car floor by screws 58 or otherwise, and which angle is provided with an upstanding flange 59 positioned between the adjacent marginal flanges 60 of the floor sheets 52. The marginal flanges 60 are secured to the flange 59 by a single line of welding material 61.

In Figure 9 we have shown an alternate means of securing the floor sheets to the car floor. A relatively small piece of flat metal 65, rectangular in form, is slit or cut along its medial line for about half its length. The material on opposite sides of said cut or slit is bent in opposite directions to extend at right angles to the remainder, as shown at 66 and 67. Recesses are formed in the sub-floor 13 to receive said laterally extending wings or portions 66 and 67 and holes 68 are provided therethrough for the application of screws 69 to secure said fastener 65 to the floor. (See Figure 1 also.) Several of these clips are so placed along the longitudinal center line of the car so that the flanges 16-16 of adjacent sheets abut flatwise against the sides of the portion 65 and all are secured together by a line of welding 70. There is a similar row of welding material 71 joining the abutting end flanges 22 of the sheets. Between the spaced clips the adjacent flanges 16-16 abut directly and are welded together. At the ends of the car the end flanges of the sheets are secured to the end of the car. Thus the steel floor of the car is welded into an integral unit with side and end sheets and insures that no moisture can pass therethrough to the insulation. It provides a means whereby the floor racks can be raised or removed, and the floor then flushed out with a hose and cleaned of all debris, etc., which, with the water, will run out of the drain.

In Figure 10 the inner side sill 75 is shown as an ordinary angle bar, which is arranged so that one arm 76 extends vertically up to the plane of the underside of the margin 77 of the floor sheet and is welded to the outer wall 78 of the gutter, as shown at 79. The inner wall 80 is provided with a flange 81 projecting over the gutter upon which flange the outer margins of the floor sheet 82 rests and is welded thereto, as at 83. This construction provides adjustability for variations in dimensions of the floor sheets and also provides a very convenient groove for welding the floor sheet to the gutter, and an anti-splash baffle to prevent water in the gutter from surging up toward the seam.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

We claim:

1. A floor for a refrigerator car having an insulated wall including a vertical flue adapted to conduct air and liquid to the floor of said car; and a bottom chord for said wall; said floor comprising a member formed with a body portion forming the floor of the car, and an upwardly extending flange bearing against said chord and joined thereto, and an inwardly extending reflare to prevent water on said floor from surging against said joint, said flue having a part overlying said reflare.

2. A floor for a refrigerator car having an 75 insulated wall including a vertical flue adapted

to conduct air and liquid to the floor of said car; and a bottom chord for said wall having an upwardly extending flange; said floor comprising a sheet formed with a body portion forming the floor of the car, an upwardly extending flange bearing against said chord, and an inwardly extending reflange, said chord flange having a downwardly and inwardly inclined portion engaging and overlying said floor reflange, and means to secure said portion and said reflange together to form a tight joint and to prevent water passing therethrough to the insulation.

3. A floor for a refrigerator car having an insulated wall including a vertical flue adapted to conduct air and liquid to the floor of said car; and a bottom chord for said wall having an upwardly extending flange; said floor comprising a sheet formed with a body portion forming the floor of the car, an upwardly extending flange bearing against said chord, and an inwardly extending reflange, said chord flange having a downwardly and inwardly inclined portion engaging and overlying said floor reflange, and means to secure said portion and said reflange together to form a tight joint and to prevent water passing therethrough to the insulation, said flue having a part overlying and secured to said portion, whereby water from said flues or on said floor is prevented from surging upwardly at the sides of the car.

4. A floor for a refrigerator car, said floor comprising a member formed with a body portion forming the floor of the car, an upwardly extending flange, and a downwardly and inwardly extending reflange, whereby water on said floor is prevented from surging upwardly at the sides of the car.

5. A floor for a refrigerator car having an insulated wall including a vertical flue, said floor comprising a body portion and a channel-shaped gutter portion, the outer part of said gutter portion being formed of an upstanding flange having a downwardly and inwardly inclined reflange adapted to receive water from said flue and discharge said water diagonally into said gutter.

6. A structure as defined in claim 5 wherein the inner wall of said gutter is provided with a lateral flange for supporting the outer margins of the body portion, the edge of said body portion terminating short of the width of said flange to provide a groove for welding said portion to said flange.

7. A structure as defined in claim 5 wherein the inner wall of said gutter is provided with a lateral flange projecting over said gutter for supporting the outer margins of the body portion and providing means to prevent surging of liquid in said gutter from splashing out of said gutter.

8. A floor for a refrigerator car having an insulated side wall including a vertical flue, said floor comprising a body portion downwardly inclined from the longitudinal middle of the car and a channel-shaped gutter portion, the outer part of said gutter portion being formed of an upstanding flange having a downwardly and inwardly inclined reflange adapted to receive water from said flue and discharge said water diagonally into said gutter.

9. A floor for a refrigerator car having an insulated wall including vertical posts and a vertical flue adapted to conduct air and water to the floor of the car, said floor comprising a body portion, and a channel-shaped gutter portion adapted to receive water from said flue, the outer part of said gutter portion being formed of an

upstanding flange having a downwardly and inwardly inclined reflange, said outer part of said gutter portion being secured to said posts.

10. A structure as defined in claim 5 wherein the upstanding flange of the outer part of the gutter is formed on a substantial radius to provide resiliency for adjustment of parts.

11. A floor for a refrigerator car having spaced insulated walls each including a vertical flue adapted to conduct air and water to the floor of the car, said floor comprising gutter portions adapted to be positioned adjacent said walls respectively to receive water from said flues respectively, the outer part of each gutter portion being formed of an upstanding flange having a downwardly and inwardly inclined reflange, body portions extending from each gutter portion to adjacent the longitudinal middle of the car, and waterproofed means secured to the car body at the juncture of said body portions to hold said body portions down.

12. A structure as defined in claim 11 wherein said means comprises a member having a horizontal flange secured to the car body and a vertical flange positioned between vertical flanges formed on said body portions and welded material securing said vertical flanges to the flanges of said body portions.

13. A floor for a refrigerator car having spaced insulated walls each including vertical posts and a vertical flue adapted to conduct air and water to the floor of the car, said floor comprising gutter portions secured directly to said posts and adapted to be positioned adjacent said walls respectively to receive water from said flues respectively, the outer part of each gutter portion being formed of an upstanding flange having a downwardly and inwardly inclined reflange, body portions extending from each gutter portion to adjacent the longitudinal middle of the car, and waterproofed means secured to the car body at the juncture of said body portions to hold said body portions down.

14. A floor for a refrigerator car having spaced insulated walls each including a vertical flue, said floor comprising gutter portions adapted to be positioned adjacent said walls respectively, the outer part of each gutter portion being formed of an upstanding flange having a downwardly and inwardly inclined reflange adapted to receive water from said flues respectively and discharge said water diagonally into the adjacent gutter, and body portions extending to and between said gutter portions.

15. A floor for a refrigerator car having spaced insulated walls each including vertical posts and a vertical flue adapted to conduct air and water to the floor of the car, said floor comprising gutter portions adapted to be positioned adjacent said walls respectively to receive water from said flues respectively, the outer part of each gutter portion being formed of an upstanding flange having a downwardly and inwardly inclined reflange, a plurality of body portions extending to and between said gutter portions, and waterproofed means secured to the car body at the juncture of said body portions to hold said body portions down.

16. A floor for a refrigerator car having an insulated wall including a vertical flue having a downwardly and inwardly inclined lower margin, which flue is adapted to conduct air and water to the floor of the car, said floor comprising a body portion, and a channel-shaped gutter portion adapted to receive water from said flue, the

outer part of said gutter portion being formed of an upstanding flange having a downwardly and inwardly inclined reflare substantially in the plane of said margin.
